SCAFFOLDING AND LIKE CLIP OR CLAMP

Allan Macbeth, Bowdon, Altrincham, England,
assignor to Mills Scaffold Company Limited,
London, England, a British company

Application January 21, 1936, Serial No. 60,146
In Great Britain February 2, 1935

4 Claims. (Cl. 304—40)

This invention relates to clips or clamps for connecting together in a detachable manner tubular or other structural members used in the erection of scaffolding, staging, fencing and for other analogous purposes. The chief object of the invention is to evolve a generally improved form of clip or clamp which can be both easily and cheaply manufactured which will have the minimum number of component parts and which 5 furthermore can be quickly and easily placed in position and removed when required.

A clip or clamp according to the invention for the purposes specified comprises two integrally formed or connected parts each of substantially 15 U shape and each adapted to embrace partially one of the tubular or other structural members to be connected, and a bolt carried by each U-shaped part for drawing its associated arms firmly into engagement with its associated structural member.

Although it is within the scope of the invention to construct the two U-shaped members integrally in which case they are pressed out of a plate or sheet of steel or other suitable material, 25 it is preferred for the sake of economy of material to construct the U-shaped members separately and to secure them together by suitable means, each U shaped member being formed from strip metal, the strip metal blank being 30 bent to the appropriate shape. The U-shaped members if constructed separately may either be immovably connected together or alternatively they may be loosely riveted together by means of a single rivet or other connecting member or 35 part, so that the two parts are free to turn relatively to each other or alternatively have a restricted turning movement.

In order that the said invention may be clearly understood and readily carried into effect, the 40 same will now be described more fully with reference to the sheet of drawings, wherein:—

Figure 1 is a front elevation of one form of clip or clamp constructed in accordance with the invention in position upon two tubular structural members.

Figures 2 and 3 are respectively a side elevation and plan view of same.

Figure 4 is a front elevation of a modified form of clip or clamp.

50 In the construction illustrated by Figures 1-3, the clip or clamp (hereinafter referred to as a clip) consists of two parts each of substantially U shape and preferably formed from strip steel or other similar metal bent to the appropriate 55 form. The two U-shaped parts 1 and 2 are con-

nected together with an interlocking engagement as shown clearly in Figures 1 and 2 the arms of each U shaped member being bent inwardly as at 3 after the two parts have been placed together to maintain the two parts in firm interlocking engagement, the two U shaped parts of the clip each embracing partially one of the structural members 4 to be connected and serving to hold the two structural members in a position at right angles to one another. Each 10 structural member preferably contacts with the adjacent face 5 of the intermediate portion of its associated U shaped part the arms being bent to contact with the structural member over a substantial proportion of its circumference. 15

Although it is within the scope of the invention to connect the arms of each U shaped part together by means of an ordinary bolt it is preferred that a bolt of the kind shown shall be employed.

One arm of each of the U shaped parts is extended upwardly and outwardly to form an outwardly projecting upwardly inclined lip 6 slotted at 7 to receive the shank of a bolt 8, the opposite arm being also slotted as at 9 to also receive the shank the axes of the two slots lying in planes at right angles to each other. The bolt is provided with a head 10 preferably of square or rectangular shape having oppositely arranged inclined faces 11 and 12 either of which can be 20 made to engage the adjacent inclined face of the lip portion of the arm by reversing the position of the bolt. The inclined faces 11 and 12 are arranged eccentrically relatively to the axis of the bolt for a purpose hereinafter described. It is 25 desirable that the shank of the bolt shall engage the surface of the adjacent structural member in order to maintain the latter firmly in engagement with the face 5 and the inner curved surfaces of the arms of the clip and by constructing the bolt in such a way that the inclined faces 30 are disposed eccentrically any variations of diameter to a reasonable degree occurring between different structural members may be compensated for by reversing the position of the bolt i. e. 35 by turning the bolt through an angle of 180°. The bolt is provided with a securing nut 13 which upon being tightened will cause the two arms to be drawn inwardly into firm engagement with the structural member and at the same time 40 cause the one inclined face on the bolt head to ride up the adjacent inclined face on the lip into the position shown in Figure 1, in which position the bolt contacts with the adjacent surface 45 of the adjacent structural member.

In order to place the clip in position upon the structural members it is not necessary to remove either the nuts or the bolts due to the arrangement of the slots and to prevent removal of the 5 nuts and the possibility of them becoming mislaid the extremities of the bolts may be burred over. The arrangement is such that the bolts are always in engagement with the slots 7 but can be released from the slots 9 by slackening the 10 nuts and moving the bolts first laterally and then in an upward and downward direction respectively. To enable the bolts to be moved laterally out of the slots 9 the slots 7 are made of sufficient 15 width to give the requisite freedom of movement between the sides of said slots and the shanks of their associated bolts.

In the construction shown by Figure 4 reference characters similar to those used in connection with Figures 1-3 designate similar parts, the 20 two substantially U-shaped parts of the clip and their associated bolts corresponding substantially with those parts previously described. In the modified arrangement however the two U-shaped parts are not rigidly connected together but are 25 loosely connected by means of a rivet or like connecting member 14 whereby the two parts are free to turn relatively to each other, the construction being intended for use primarily in cases where the structural members to be connected 30 are not disposed necessarily at right angles to one another. Alternatively more than one rivet may be employed in which case the parts will be rigidly connected, or by a suitable arrangement of slots connected with a limited amount 35 of turning movement.

In both constructions illustrated the lower bolt has been omitted from the drawing to show the form and disposition of the slots more clearly. Although the bolt has been described as having 40 only two oppositely arranged inclined faces and having a head of square or rectangular shape it may be provided with four or any other desired number of faces to increase the range of adjustment.

45 The U-shaped parts may be constructed from steel or other suitable material and may be tempered if desired to increase their resiliency if this is found to be desirable. Furthermore although in the constructions illustrated the U-shaped parts are shown constructed separately they nevertheless may be pressed or otherwise formed from a single piece of metal, the metal blank being substantially in the form of a cross, two oppositely arranged arms being bent in one direction to form the one U-shaped part and the other pair of arms bent in the opposite direction to form the remaining U-shaped part.

What I claim and desire to secure by Letters Patent of the United States is:—

1. A scaffolding clip for securing together in angular relationship two metal tubes or rods employed in the erection of scaffolding, comprising two substantially U-shaped members hooked together in interlocking engagement and each adapted to embrace partially one of the tubes or rods to be connected, each substantially U-shaped member including two substantially parallel arms, securing bolts passing through slots formed in said arms for maintaining said arms in clamping engagement with said tubes or rods and an inclined lip formed on one of each pair of arms, each securing bolt having a head provided with an inclined face for cooperating with said inclined lip for the purpose of adjustment. 5

2. A clip of substantially U-shape to embrace a pipe or rod, said clip including a pair of arms having free end portions, a bolt extending through the free end portions of said arms for drawing them together into clamping engagement with a pipe or rod, and means whereby tightening of said bolt urges the same inwardly relative to the clip for clamping contact with the pipe or rod, said means including an inclined lip at the free end of one of the arms, and a head on the bolt cooperating with said lip. 10

3. A clip of substantially U-shape to embrace a pipe or rod, said clip including a pair of arms having free end portions, a bolt extending through the free end portions of said arms for drawing them together into clamping engagement with a pipe or rod, and means whereby tightening of said bolt urges the same inwardly relative to the clip for clamping contact with the pipe or rod, said means including an inclined lip at the free end of one of the arms, and a head on the bolt cooperating with said lip. 15

30

4. A clip of substantially U-shape to embrace a pipe or rod, said clip including a pair of arms having free end portions each having a slot, the 35 free end portion of one of said arms being in the

form of an outwardly inclined lip, a headed bolt 40 extending through the slots in said arms, a nut on said bolt for drawing said arms together, the bolt head cooperating with said lip when the nut is tightened to urge the bolt inwardly relative to the clip into engagement with the pipe or rod, 45 the slot in the arm with which the nut cooperates opening through the side of said arm to permit engagement and disengagement of the bolt from said arm, and the slot in the other arm extending into said lip to permit the bolt to be swung 50 to a position substantially in alignment with the last mentioned arm. 55

ALLAN MACBETH.
